(57) **CLAIM**

The ornamental design for an display screen or portion thereof with animated graphical user interface, as shown and described.

DESCRIPTION

FIG. 1 is a front view of a first image of a first embodiment of a display screen or portion thereof with animated graphical user interface showing our new design;

FIG. 2 is a front view of a second image of the first embodiment;

FIG. 3 is a front view of a third image of the first embodiment; and

FIG. 4 is a front view of a fourth image of the first embodiment.

FIG. 5 is a front view of a first image of a second embodiment of a display screen or portion thereof with animated graphical user interface showing our new design;

FIG. 6 is a front view of a second image of the second embodiment;

FIG. 7 is a front view of a third image of the second embodiment; and,

FIG. 8 is a front view of a fourth image of the second embodiment.

The appearance of the animated images transitions between the images shown in FIGS. 1-4 and FIGS. 5-8. The process or period in which one image transitions to another forms no part of the claimed design.
